COMMODITY BAG

Dominic A. Perino, Milwaukee, Wis., assignor to
Milprint, Inc., Milwaukee, Wis., a corporation
of Delaware

Application October 5, 1949, Serial No. 119,644

2 Claims. (Cl. 150—11)

1

The present invention relates generally to improvements in the art of manufacturing commodity bags, and relates more particularly to improvements in the construction and use of bags or pouches having re-usable closures.

A primary object of the invention is to provide an improved re-usable commodity receiving and transporting bag which is extremely simple and durable in construction and highly attractive in appearance, and which may moreover be merchandised at low cost.

For many years, it has been customary to produce commodity bags and pouches of relatively inexpensive sheet materials, such as transparent "cellophane," "Pliofilm" and other plastics or the like which, although inexpensive, are readily fabricated into bags which are exceedingly durable and tear resistant. These bags and pouches have heretofore been put to a great many uses, especially in the packaging of diverse commodities for display and/or merchandising purposes; and due to the relatively inexpensive and durable qualities of these materials, the containers fabricated therefrom are readily adapted for such purposes and serve to effectively protect the packaged articles until after use thereof by the consumer. However, since these bags and/or pouches are usually intended primarily for protective purposes for specific commodities and, as such, are more-or-less permanently sealed after packaging, they are ordinarily destroyed or discarded by the consumer after removal of the packaged article or articles therefrom.

It is accordingly a more specific object of my present invention to provide an improved bag which may be readily fabricated of inexpensive sheet material, and which is nevertheless exceptionally sturdy and capable of repeated use for transporting diverse articles.

Another specific object of this invention is to provide an improved and highly useful commodity receiving and transporting bag-like receptacle having an extremely flexible transparent body of sheet material, and provided with a novel reinforced mouth adapted for ready opening and closing.

Another specific object of the invention is to provide an improved commodity bag adapted to be produced in large quantities at low cost from inexpensive sheets of cellulosic, rubber hydrochloride and other plastic materials, and having a commodity receiving opening or mouth adapted to facilitate filling of the bag.

Still another specific object of the present invention is to provide an improved marketing bag having an exceedingly flexible body and a relatively rigid filling mouth adapted to be quickly and easily opened and closed with the aid of drawstrings only.

An additional specific object of the present invention is to provide a new and improved bag

5

which may be utilized for display and merchandising of diverse commodities and which may thereafter be re-used by the consumer for carrying other desired articles, novel closure means being provided for this purpose.

10 A further specific object of the present invention is to provide an improved commodity bag comprising, a flat tubular body of flexible sheet material having a closed bottom and an open mouth, a relatively rigid strip secured to the body and extending along the mouth and provided with a series of transverse score lines, and means cooperable with the strip to cause folding thereof at the score lines to open and close the bag mouth.

15 These and other specific objects and advantages of the invention will be apparent from the following detailed description.

20 A clear conception of the several features constituting the present improvement, and the mode of producing and of utilizing commodity bags embodying the invention, may be had by referring to the drawing accompanying and forming a part of this specification, wherein like reference characters designate the same or similar parts in the various views.

25 Fig. 1 is a plan view of one of the improved empty commodity bags;

30 Fig. 2 is a perspective view of one of the bags, showing the mouth in partially closed condition after insertion of the commodity;

35 Fig. 3 is a top view of the bag with the mouth partially closed;

40 Fig. 4 is another top view of the bag with the mouth in substantially closed condition; and

45 Fig. 5 is a top view similar to Fig. 3, but showing the invention applied to a gussetted type of bag.

While the invention has been shown and described herein as being specifically applied to a bag of a particular size and shape and produced of certain known materials, it is not my desire or intent to thereby unnecessarily restrict or limit the scope or utility of the improvement.

50 Referring to the drawing, the improved commodity receiving and transporting receptacle shown therein by way of illustration comprises, in general, a flat tubular body 10 formed from adjoining sheets of flexible material united along the side edges 11 and bottom edges 12 in a suitable manner, as by heat sealing or with the aid of adhesives, and having an open upper end or mouth 13; a relatively rigid band or strip 14 secured to the body 10 along the mouth 13 thereof, the strip 14 being provided with a series of transverse score lines 15 dividing the same into a plurality of similar adjoining rectangular sections 16, each having a medial aperture 17 therein aligned with a corresponding series of holes in the adjacent body wall; and means cooperable with the strip 14 to cause folding thereof at the

score lines 15 to open and close the bag mouth 13 as will hereinafter more fully appear, said means comprising a pair of draw strings 18, 19 interlaced with the openings 17 of the successive sections or panels 16.

The bag body 10 may be fabricated in a known manner from transparent plastic sheet materials such as "cellophane" or "Pliofilm," and if desired, this bag may be of the well-known gussetted type shown in Fig. 5 instead of the flat type illustrated in the other views. If the material utilized in producing the bags is of the type which is sealable upon application of heat and pressure, the seams 11, 12 may be formed by heat-sealing, otherwise the edges may be sealed with the aid of adhesives; and for advertising or like purposes, the side walls of the body 10 may be provided with printed matter in the usual manner. The upper strip 14 may be formed from any suitable relatively stiff material such as cardboard; and this strip may be in the form of a continuous band surrounding the mouth, or corresponding strips 14 may be secured to each of the side walls of the body 10 along a substantial portion of the mouth 13 as shown. To insure proper folding or creasing of the strip 14 along the successive score lines 15 in alternate directions upon manipulation of the strings 18, 19, the score lines may be alternately imposed on the front and rear surfaces of the strip 14, or they may consist of alternate full and partial scoring. The strips 14 may be secured to the side walls of the bag body 10 in any suitable manner, as by adhesives or staples; and these strips may also bear printed advertising indicia or the like. The draw strings 18, 19 are each of sufficient length to encircle the bag mouth 13 and to additionally protrude somewhat at opposite ends to permit the units to be packaged and shipped in flat condition as well as to facilitate grasping of the strings; and to further facilitate manipulation of the closure means, the strings 18, 19 may be of different colors.

The operation of the improved commodity receiving and transporting bag is as follows: After the articles are placed within the bag body via the mouth 13, it is only necessary to grasp the opposite protruding ends of the respective draw strings 18, 19 and pull the same in opposite directions, thereby drawing the strings through the openings 17 and causing them to coact with the end panels 16 of the strips 14 to fold the strips along the score lines 15 as shown in Figs. 2, 3 and 5. As the strings 18, 19 are pulled with greater force, the folding of the strips 14 continues with the successive sections or panels 16 thereof being brought closer together, as shown in Fig. 4, until adjoining sections 16 lie against each other, thus closing the bag mouth. To open the mouth 13, it is only necessary to release the pull on the respective strings 18, 19 and thereafter insert fingers in the mouth and force the end sections 16 of the respective strips away from each other in an obvious manner.

From the foregoing detailed description, it is believed apparent that my invention provides an improved commodity receiving and transporting bag which is simple and durable in construction and which, moreover possesses considerable utility. The improved bags may be utilized for displaying and merchandising diverse commodities, such as apples, oranges, potatoes and numerous other items, in a novel and attractive manner and may thereafter be used and re-used as a shopping bag or the like. The bag body 10 may be rapidly produced in large quantities and at low

cost with the aid of automatic equipment, and the side walls thereof may be printed or they may be perforated as is customary when utilized for certain fruits and vegetables. After loading of the bag and closing of the mouth with the aid of the draw strings, these draw strings 18, 19 may be conveniently used as a gripping device for carrying the bag; and the relatively rigid scored strip or strips 14 not only serve as a reinforcement for the bag mouth 13, but also considerably facilitate opening and closing of the mouth and loading and emptying of the bag. As indicated hereinabove, the closure may be applied either to the flat bags or to bags of the gussetted type with equal success, and commodity bags embodying the novel features have proven commercially practical.

It should be understood that it is not desired or intended to limit this invention to the exact details of construction, or to the precise mode of use, herein shown and described, for various modifications within the scope of the appended claims may occur to persons skilled in the art to which this invention pertains; and it is also contemplated that specific descriptive terms used herein be given the broadest possible interpretation consistent with the disclosure.

I claim:

1. A commodity receiving and transporting bag comprising, a normally flat tubular body formed of corresponding sheets of flexible plastic-like material seamed along edge portions to provide a closed bottom and an open mouth, a pair of relatively rigid cardboard strips secured to opposite sides of said body and extending along the bag mouth but terminating short of the bag edge seams and provided with corresponding series of transverse score lines dividing said strip into a plurality of similar adjoining rectangular sections, each section being provided with a medial aperture, and a pair of draw strings interlaced with the apertures of said successive sections and manipulatable at opposite ends of said strips to cause simultaneous folding of said strips to thereby close the bag mouth.

2. A commodity receiving and transporting bag comprising, a normally flat tubular body of flexible plastic-like sheet material having a closed bottom and an open mouth, a pair of relatively rigid strips secured to opposite sides of said body and extending along but terminating short of the ends of the bag mouth and provided with corresponding series of transverse score lines, and a pair of drawstrings cooperable with said strips and manipulatable at opposite ends thereof to cause folding of said strips at the score lines to open and close the bag mouth.
